UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

1,242,147.

Specification of Letters Patent. Patented Oct. 9, 1917.

Application filed March 26, 1917. Serial No. 157,394.

To all whom it may concern:

Be it known that I, GEORGE CLAUSING, a citizen of the United States, and a resident of the city of Portsmouth, in the county of Scioto and State of Ohio, have invented certain new and useful Improvements in Lasts, of which the following is a specification.

One of the objects of the invention is to produce a simple, strong and practical last which can be broken or flexed so as to facilitate the ready removal of the last from the shoe and so that the shoe during the removal of the last will not be marred, broken, or pulled out of shape.

It has been found practical to construct a last so that it will comprise toe and heel parts which have provided between them a pair of main bearing pins which extend transversely of the last. The toe and heel parts preferably bear directly against these pins which are held in place so that the heel part can swing relatively to the toe part in order to break or shorten the last. It has also been found practical to secure said toe and heel parts together by a link that is directly connected at one end to the toe part and at the other end to the heel part by small pivot pins or rivets that pass through the end portions of the link. It is also preferable, in the construction of such lasts, to provide a tension spring which tends to maintain the parts of the last in unbroken position. This spring is preferably located below the center of the main bearing pins and it is also located below the link just referred to.

According to the present invention this link is composed of pivotally connected members, preferably a pair of members which are connected by a pivot that is located adjacent to the main bearing pins. With this construction a last can be made in which the parts can be moved to effect a considerable shortening of the last and this can be accomplished without necessitating the removal of as much material from the parts of the last as would be necessitated to effect the same shortening, if the link were of a single member.

As showing a specific embodiment of the invention reference is made to the drawings forming a part of this specification and in which drawings,

Figure 1 is a side elevation of a last with the parts in extended or unbroken position.

Fig. 2 is a plan view of the last shown in Fig. 1.

Fig. 3 is a vertical sectional view taken as on the plane indicated by the line 3—3 of Fig. 2.

Fig. 4 is a sectional view showing the position of the parts of the last when in a full broken or extreme shortened position.

Fig. 5 is a sectional view taken as on the plane indicated by the line 5—5 of Fig. 1 looking in the direction of the arrows.

Fig. 6 is a vertical sectional view taken as on the planes indicated by the broken lines 6—6 of Fig. 1 looking in the direction of the arrows.

Fig. 7 is a view of the toe part of the last and of the end thereof nearest to the heel part of the last.

The last is designated by the reference character A and comprises the forward or toe part B and the rear or heel part C. In the formation of the last these two parts are made integral with each other from the same piece of wood and they are subsequently separated, as by sawing, along the lines X Y, X Z, M N and Y O. After the proper saw-cuts have been made the parts of the last can be separated by splitting the wood along the line Z M. This construction is employed where it is desired to have horizontally extending overlapping shoulders between the toe part and the heel part of the last. It is practicable, however, to make the last without the employment of the overlapping shoulder. Preferably some time before the heel and toe parts are finally separated a hole is bored at Y to form grooves for the reception of the main bearing pins D and D'.

The material which formerly occupied the space defined by the lines X Y and Y O is removed from the finished last and there is left a V-shaped opening which permits the parts of the last to assume the position shown in Fig. 4, as will be manifest from an inspection of the drawings. By suitable apparatus a cavity or opening, such as is shown in Figs. 3 and 7, can be made in the toe part of the last and a similar cavity or opening can be provided in the heel part of the last.

Into the upper part of these cavities or openings there extends a link E one end of which link is secured in place to the toe part of the last by a small rivet or pin e and the other end of this link is secured to the heel part of the last by a small

110

rivet or pin e' . There extends into the lower portion of each of these cavities or openings a tension spring F , one end of which spring is secured by a small pin or rivet f to the toe 5 part of the last and the other end of which spring is secured by a small pin or rivet f' to the heel part of the last. This spring may be omitted in some forms of last but it is preferable to include this spring in the 10 last and it is arranged so that it tends to maintain the heel and toe parts of the last in extended position.

An important feature of the present invention resides in the constructing of the 15 link E —which is of metal—above referred to of pivotally connected members and in the form shown this link is made of a pair of members G and H which are pivotally connected by means of a rivet or pin K . The 20 member G may be considered to comprise a pair of leaves g and g' which are connected by the metal at g^2 . In other words, the member G is of U-shape, but a single plate or a pair of connected plates could be employed at this place. The pivotal connection between the members G and H is located at or near the center of the link, to wit, in the central portion of the link; in 25 other words, intermediate the place where the ends of the link are connected respectively to the heel part and toe part of the last. The ends of the link members which are connected by the pivot pin K may be considered as the fixed ends of said members 30 and the ends of said link members which are connected to the toe part and heel part respectively may be referred to as the movable or free ends of the link members. When the parts of the last are in the extended position 35 shown in Fig. 1 it will be observed that the longitudinally extending line $e\ e', e'\ e$ passing through the centers of the pivot pins e and e' is located below a horizontally and transversely extending line which passes 40 through the centers of the main bearing pins D and D' , and it will also be observed that when the parts of the last are in extended or unbroken position the center Kc of the pivot connection K is on this line $e\ e'-e'\ e$, if the 45 members of the link are free to assume this position. As the parts of the last start to move from an extended or unbroken position toward a broken position, as by an upward swinging movement of the heel part of the last, the center of the pivot connection K starts to move toward the line passing 50 through the center of the main bearing pins D, D' . The upward movement of the pivotal connection is a limited movement and said movement is or can be arrested by the link member G striking the roof L of the cut-out portion in the toe part of the last and an upward movement of the heel part can continue to take place due to the flexing or

breaking of the link E , which flexing or 55 breaking is permitted as a result of the pivotal connection at K . During this last mentioned period the member H of the link E will swing about the pivotal center Kc . It is practical to make this construction so 60 that the pivotal center Kc will proximate or substantially coincide with the center line passing through the main bearing pins D, D' when the upward movement of the member G is arrested, as by engagement with the 65 roof L , and it is also practical to make the construction so that the center Kc will move, from a position below the line passing through the centers of the main bearing pins D, D' to a position above this line before the 70 movement of the member G is arrested, as by engagement with the roof L . It will be noted that the pins e and e' are on opposite sides of the vertically or transversely extending plane which passes through the 75 centers of the main bearing pins D and D' . When the parts of the last are in extended or unbroken position the center of the pivotal connection between the members G and H which constitute the link is preferably located below the center of said main bearing pins and in substantially the plane just referred to. In other words, the pin, rivet or 80 pivotal connection K is located between the 85 rivets or pins e and e' adjacent to the main bearing pins D and D' . During the first portion of the movement of the heel part toward broken position the rivet K is caused to approach the main bearing pins D and D' . During the latter portion of the movement 90 of the heel part toward the toe part this rivet K remains in a substantially fixed position relative to the main bearing pins D and D' . The pivotal connection of the link members always remains proximate the center 95 line of axis of said pins. The link construction is such that the link always holds or maintains the last parts in proper position relative to each other whereby the last parts will remain assembled whether they be in an 100 extended or unbroken position or a full broken position, or a position intermediate the unbroken and broken positions. The link construction is also such that the swinging of each link member relative to the last part to which it is connected is a limited 105 movement that takes place during the first portion of the movement for breaking the last and during the final movement of the last parts toward unbroken position.

The main bearing pins D and D' have shoulders or collars thereupon (preferably sharp) designated by d and d' which can be forced into the wood so as to serve as means for retaining the bearing pins D and D' in position, as against any longitudinal displacement, without necessitating the employment of a screw or nail for secur-

ing said bearing pins D and D' to one or the other of the parts of the last. The link E is, of course, located between the bearing pins D and D' and can thus serve to maintain the parts in proper position when the last is in use.

The improvements herein set forth are not limited to the precise construction and arrangement shown and described for they 10 may be embodied in various forms and modifications without departing from the spirit and scope of the invention.

What I claim and desire to secure by Letters Patent of the United States is:

15 1. A last comprising a heel part and a toe part having provided between them main bearing pins against which each of the parts of the last bear, the last being provided with a connecting link composed of 20 members which are pivotally connected, one to the other, at the central portion of the link, one end of said link being pivotally secured to the toe part and the other end being pivotally secured to the heel part 25 whereby said link connects said toe part to the heel part, said link being positioned so that a line passing through the center of the pivots which connect said link to the heel and toe parts will be located below the 30 center of the main bearing pins when the parts of the last are in extended position but so that said line approaches the center of said bearings upon the movement of the heel part upwardly from its extended or unbroken position, the construction being such 35 that during a substantial part of the final movement of the operation of breaking the last the pivotally connected members of the link will be permitted to move relatively 40 to each other due to the pivotal connection which is at the central portion of the link.

2. A last comprising a heel part and a toe part having between them horizontally and transversely extending main bearing 45 pins, the last being also provided with a link composed of pivotally connected members one end of said link being connected to the toe part and the other end of said link being connected to the heel part, and a spring 50 that is continuously under tension connected to said heel and toe parts so that they will be continuously drawn against the main bearing pins, the spring also being arranged so that the heel and toe parts will tend to 55 be maintained in extended or unbroken position when in said position, the link being constructed and arranged so that the pivotally connected members thereof will be in extended or unbroken position when 60 the heel and toe parts are in an extended or unbroken position and so that the pivoted members of said link can be moved to a broken or partially folded position when the heel and toe parts occupy a full broken 65 or shortened position.

3. A last having a grooved toe part and a grooved heel part which have horizontally and transversely extending main bearing pins that are in the grooves in said parts, the last also being provided with a link for 70 connecting and holding the heel and toe parts together, one end of said link being directly connected by a pin or rivet to the toe part of the last, the other end of the link being directly connected by a pin or rivet 75 to the heel part of the last, said link being located so that a line passing through the center of said rivets will be located a slight distance below the center of the main bearing pins when the heel part and toe part are 80 in the extended or unbroken position but so that said line will approach the center of said main bearing pins when the heel part is swung upwardly from extended position, said link being composed of members which 85 are connected by a pivotal connection that is located between the places where the ends of said link are pivotally connected, respectively, to the heel part and to the toe part, the construction being such that upon the 90 continued movement of the heel part to full broken position the link will be broken or flexed by one of the members of the link swinging relative to its companion member to which it is pivotally connected. 95

4. A last having heel and toe parts provided between them with main bearing pins against which each part of the last bears, the last being provided with a link having one end secured to the toe part and the 100 other end secured to the heel part, said link being positioned so that a line passing through the center of the pivots which connect the ends of said link to the heel part and the toe part will swing upwardly from 105 below the center of the bearing pins as the heel part is swung upwardly relative to the toe part, said heel and toe parts also having provided between them means which tend to maintain said parts in extended or unbroken position when they are in said position, the link being composed of members 110 which are pivotally connected at or near the bearing pins.

5. A last having an upwardly extending 115 cut which divides the last into heel and toe parts, there being provided at the upper portion of the last a V-shaped opening whereby the heel part of the last can move relatively to the toe part of the last in order 120 to break or shorten the last, the heel part of the last being provided at the bottom of the V-shaped opening with a pair of spaced main bearing pins that serve as bearings against which said heel and toe parts press, 125 said heel and toe parts being connected by a link which is secured at one end by a rivet to the toe part and at the other end by a rivet to the heel part, which rivets are located upon opposite sides of the vertical 130

24

plane passing through the centers of said pair of spaced bearing pins, said link being positioned so that a line passing through the center of the pins which connect the link to said heel and toe parts is located below the center of the bearing pins when the parts of the last are in extended or unbroken position, said link being composed of pivotally connected members the center of which last-mentioned pivotal connection is located substantially in the vertical plane passing through the center of the main bearing pins and below a line passing through the center of said bearing pins when the parts of the last are in extended or unbroken position.

6. A last comprising in combination a toe part, a heel part movable relatively to the toe part, which last parts swing relatively to each other on transversely extending bearings, and a link for connecting said last parts and for holding such last parts together in all positions of said last parts relative to each other, one end of said link being pivotally connected to the toe part of the last the other end of said link being pivotally connected to the heel part of the last, the link being composed of members pivotally connected proximate the center line passing through said transversely extending bearings so that said link members can swing relatively to each other during the breaking or shortening of the last, the construction being such that the member of the link which is connected to the toe part of the last will swing relatively to said toe part and so that the member of the link which is connected to the heel part of the last will swing relatively to said heel part.

7. A last comprising in combination a toe part, a heel part movable relatively to the toe part which last parts swing relatively to each other on transversely extending bearings, and a link for connecting said last parts and for holding said last parts together in all positions which they assume relatively to each other, one end of said link being pivotally connected to the toe part of the last and the other end of said link being pivotally connected to the heel part of the last, the link being composed of members pivotally connected so that said link members can swing relatively to each other during the breaking or shortening of the last, the construction being such that the member of the link that is connected to the toe part of the last will swing relatively to the toe part and so that the member of the link that is connected to the heel part will swing relatively to said heel part, the construction also being such that the swinging of each link member relatively to the last part to which it is connected is a limited movement that takes place during the first portion of the movement for breaking the last and dur-

ing the final portion of the movement toward unbroken position.

8. A last comprising in combination a toe part, a heel part movable relatively to the toe part, which parts swing relatively to each other on transversely extending bearings, and a link for connecting said parts, one end of said link being pivotally connected to the toe part of the last the other end of said link being pivotally connected to the heel part of the last, the link being composed of members pivotally connected proximate said transversely extending bearings, so that said link members can swing relatively to each other during the breaking or shortening of the last and so that said pivotal connection can remain proximate said bearings during said breaking and shortening, the construction being such that the member of the link which is connected to the toe part of the last will swing relatively to said toe part and so that the member which is connected to the heel part of the last will swing relatively to said heel part, the construction also being such that the swinging movement of the link members relatively to the parts to which they are connected will be limited.

9. A last of the class described comprising in combination a toe part, a heel part, transversely extending bearing pins between said parts, a link having pivotally connected members the free end of one member of the link being pivotally connected to the toe part and the free end of the other member of the link being pivotally connected to the heel part, the point of pivotal connection of the link members to each other being located so that it can move into proximate alinement with the axis of the main bearing pins, the opening in which the members of the link extend being constructed so that during the latter part of the movement of the parts of the last to full broken or shortened position the link will engage one or both of said last parts whereby during the subsequent movement the pivotally connected members of the link will move relatively to each other.

10. A last having a toe part, a heel part, transversely extending main bearing pins in grooves in said parts, a link pivotally connected at one end to the toe part and pivotally connected at the other end to the heel part, each of said main bearing pins being provided with a shoulder or collar which is forced into the parts engaging the pins whereby said pins will be retained in position.

11. A last having a toe part, a heel part, transversely extending main pins in grooves in said parts, a link pivotally connected at one end to the toe part and pivotally connected at the other end to the heel part, each of said main bearing pins being provided

with a shoulder or collar which is forced into the wood of the opposing parts engaging the pin whereby said pin will be retained in position against longitudinal placement, the link serving to always maintain the heel and toe parts in proper assembled position relatively to each other.

This specification signed and witnessed this 20th day of March, A. D., 1917.
